CLAIM

The ornamental design for a rake head, as shown and described.

DESCRIPTION

FIG. 1 is a top and front perspective view of a rake head showing my new design;

FIG. 2 is a top plan view thereof;

FIG. 3 is a bottom plan view thereof;

FIG. 4 is a right side elevational view thereof, the left side being a mirror image;

FIG. 5 is a rear elevational view thereof; and,
FIG. 6 is a front elevational view thereof.

The portions of the drawings shown in broken lines are environment in which the design may be used and form no part of the claimed design.
